UNITED STATES PATENT OFFICE

HANS HARTMAN, OF LONDON, ENGLAND, ASSIGNOR TO DUPLEX VENDING MACHINE COMPANY, INC., OF NEW YORK, N. Y., A CORPORATION OF NEW YORK.

AUTOMATIC VENDING-MACHINE.

1,142,702.

Specification of Letters Patent. Patented June 8, 1915.

Application filed December 13, 1913, Serial No. 806,476. Renewed May 1, 1915. Serial No. 25,336.

To all whom it may concern:

Be it known that I, HANS HARTMAN, a subject of the Emperor of Austria-Hungary, residing at London, England, have invented certain new and useful Improvements in Automatic Vending-Machines; and I do hereby declare the following to be a full, clear, and exact description of the invention, such as will enable others skilled in the art to which it appertains to make and use the same.

This invention relates to improvements in automatic vending machines of the kind more particularly intended for delivery of sweetmeats, cigars, cigarettes and the like and the object of the present invention is to provide an extremely simple, reliable and efficient device to this end and further to provide a neat and compact contrivance which may be readily attached to the backs of seats in places of public resort such as theaters, music halls, cinema halls and the like.

In order that this invention may be fully understood, it will now be described in reference to the accompanying drawings in which:—

Figure 1 is a front elevation of the machine with the covering door removed showing the parts in the normal position. Fig. 2 is a similar view showing the position of the essential parts after the insertion of a coin. Fig. 3 is again a similar view showing the position of the parts after the machine has been manipulated for the delivery of the goods. Fig. 4 is a side elevation of the essential parts of the mechanism with the case in section. Figs. 5, 6 and 7 are detail views showing modified forms of the invention.

In carrying this invention into practical effect the device comprises an outer casing *a* wherein the goods to be delivered are designed to be contained, the said goods, where packing is necessary, being preferably put in cylindrical form as indicated at *b*.

The bottom of the device comprises a partially rotatable semi-cylindrical tray *c* wherein the lowermost article rests. In combination with this tray a sliding locking plate *d* is provided, the lower extremity of which normally rests upon the top of the aforesaid delivery tray in such a manner as to prevent the same rotating while, in conjunction with the locking plate *d* a pivoted arm

or catch e is arranged, the extremity e' of which enters the slot d' in the locking plate d and prevents the same from sufficiently moving to allow of the rotation of the delivery tray. The said sliding locking plate 60 is provided or formed with a bent up portion or arm d^2 the purpose of which is to support the coin when inserted in the coin chute in such a manner that the coin is not allowed to drop until the delivery tray has 65 been sufficiently rotated to allow the lower-most article to pass into the delivery receptacle. The aforesaid projection or arm d^2 lifts or raises the coin and then allows it to escape from the coin chute. A plate is provided to divide the outer casing into two compartments the one containing the articles to be delivered and the other the coin chute and forming the receptacle for containing the coins. 70 75

The case is provided with a coin slot *f* beneath which is arranged a coin chute *g*, the said coin chute being perforated or more or less of skeleton form whereby ready access may be had to the interior of the same and in order that the insertion of coins may be prevented after the last of the goods contained in the machine has been delivered, a flat spring *h* is pivoted to the back of the casing and normally retained in a retracted position by the pressure of the articles contained therein.

In practice and upon a coin being inserted as shown at Fig. 2, the locking extremity *e'* of the pivoted arm or catch *e* is withdrawn from the slot *d'* in the locking plate *d*, thereby allowing of the delivery tray being rotated and whereby the locking plate is elevated while the article is delivered into a lower receptacle *i* open at each side and from which the article may be readily removed while upon the delivery tray returning to its normal position, the locking plate falls and is again engaged by the arm or catch *e*.

In the form of the invention as shown in Figs. 1 to 4, the engagement between the delivery tray and the locking plate is provided for by means of an eccentric pin *j* carried by the tray and upon which the lower extremity of the locking plate rests. When the last article has been delivered, the spring *h* is free to expand into the position shown in Fig. 4 and a catch or shoulder *h'* formed thereon, engages the lower extremity 105 110

of the locking plate, prevents the same from again falling, and in this manner sufficiently covers the coin slot so as to prevent the insertion of further coins until the machine 5 is again filled.

In order to insure the locking plate returning to its locking position when the delivery tray returns to a position for the delivery of a second article, a radial slot *k* 10 may be formed in the lower extremity of the locking plate and an eccentric pin *k'* carried on the end of the delivery tray enters therein in such a manner that when the locking plate has been elevated, the tray cannot 15 not be returned to the delivery position without the locking plate falling (Figs. 5 and 6).

In a further modification, the delivery tray may be pivotally connected to the locking 20 plate as shown at *l* (Fig. 7) and the device manipulated after the insertion of a coin, by means of a knob or arm *m* secured to the locking plate and projecting through a vertical slot in the side of the casing *a*.

25 What I claim is:—

1. In a coin controlled vending machine the combination of a containing receptacle, a rotatable delivery tray, a movable locking bar resting thereon, a locking member engaging into such locking bar, a chute having a curved or inclined portion which in connection with a projecting part of the locking bar forms a coin-rest for a coin of predetermined size whereby the coin disengages 30 the locking member from the locking bar.

2. In a coin controlled vending machine the combination of a containing receptacle, a rotatable delivery tray, a vertically movable locking bar resting thereon in such a 40 manner that it is raised when the tray is turned manually by a knob or lever, a locking member engaging into such locking bar, a chute having a curved or inclined portion which in connection with a projecting part 45 of the locking bar forms a coin-rest for a coin whereby the coin disengages the locking member from the locking bar by lifting such locking member out of a slit provided in the locking bar.

50 3. In a coin controlled vending machine, the combination of a rotatable delivery tray with a vertically movable locking bar resting thereon in such manner that it is raised when the delivery tray is rotated and closes 55 the coin inlet until the rotated delivery tray returns to its initial position and a spring

which is normally retained in a retracted position by the weight and pressure of the packages in the containing receptacle and adapted to support the raised locking bar in 60 an elevated position thus preventing the insertion of further coins when the last package has been delivered.

4. In a coin controlled vending machine, the combination of a rotatable delivery tray 65 with a vertically movable locking bar resting thereon in such a manner that it is raised when the delivery tray is rotated, a coin chute, a locking member engaging a slit in said locking bar so as to prevent its movement until a coin of predetermined size is inserted into this coin chute, said coin chute having a curved or inclined portion which, in connection with a projecting part of the locking bar, forms a coin-rest, and lifts said locking 70 member out of its initial position and a second slit in the said locking bar, underneath the first slit, with the object of securing the return of the locking member to a locked position with the locking bar, before said 75 bar returns to its initial position.

5. In a coin controlled vending machine the combination of a rotatable delivery tray with a movable locking bar resting thereon, a locking member engaging said locking bar, 80 a coin chute having a curved or inclined portion which, in connection with an arm projecting from the locking bar, forms a coin-rest for a coin of predetermined size and supports said coin in such a manner that the 85 coin lifts the locking member sufficiently to disengage it from the locking bar and whereby when the locking bar is raised, by rotating the delivery tray, the coin supporting arm passes above the coin, which, losing its supports, falls into the money receptacle. 90

4. In a coin controlled vending machine the combination of a rotatable delivery tray, a movable locking bar resting thereon, a locking catch or member engaging such locking bar which is raised when the delivery tray is manually operated and an eccentric pin carried by the rotatable delivery tray which projects into a slit formed at the lower end of the locking bar with the object to 100 cause both to travel at the same time.

In testimony whereof I have affixed my signature, in presence of two witnesses.

HANS HARTMAN.
